FOOTBALL DUMMY

Martin John Gilman, Gilman, Conn.

Application March 4, 1940, Serial No. 322,117

8 Claims. (Cl. 273—55)

This invention pertains to athletic training devices and more particularly to a dummy to be used for training athletes in the art of football.

Heretofore, football dummies have been generally classified as the self erecting type, the non-erecting type and the shiftable type. The shiftable type of dummy is one which is supported by the player and moved about during the progress of the play after the ball is snapped back and the players are in motion. The present invention pertains particularly to the self erecting type of dummy.

The Gilman Dummy Patent Number 2,037,508, issued April 14, 1936 is a packed dummy which uses a filler which may be of any suitable material such as hair, cotton, and the like. The packed self erecting dummy is extremely heavy frequently weighing between 250 and 350 pounds. The packing of this type of dummy requires particular skill and frequently requires special tools.

A packed dummy consequently is a factory packing job requiring a large amount of space for storing besides being difficult to handle when moving it from one place to another on the football field.

It is an object of this invention to provide a dummy of the self erecting type which is light in weight, and can be reduced in size for shipping and transportation.

A further object of the invention is to provide a lightweight portable dummy of the self erecting type having an inflatable or resilient member surrounding the lower portion thereof to avoid injury to the player.

A further object of the invention is to provide a self-erecting dummy having an inter-changeable container for holding the weighting means such as sand.

Other and further objects may be or may become apparent to those skilled in the art without departing in the spirit of the claims.

In the drawing:

Fig. 1 is a perspective view of the invention ready for use.

Fig. 2 is a reduced showing with parts broken away of a cross section taken substantially along the lines 2—2 of Fig. 3.

Fig. 3 is a side view partly broken away to show the weighted container, valves in the pneumatic ring, and the pneumatic upper section.

Fig. 4 is a cross section of the valve for the upper inflatable member in conjunction with the outer casing.

Fig. 5 is a section of the pneumatic ring valve in conjunction with its casing.

Referring to the drawing and particularly Figs. 1 and 3 the upper section 6 consists of two layers, an outer layer and an inner layer, 7 and 8 respectively, which layers are preferably of canvas having the warp threads of the respective layers substantially at right angles one to the other to reduce stretching of the material for the purpose of retaining the shape of the dummy casing.

Fig. 2 shows that the outer layer 7 is made of two pieces 9 and 10 which are sewed together at 11 and 12. The inner layer 8 is substantially the same as the outer layer 7 having two sections 13 and 14 sewed together at 15 and 16 respectively. The top closure 17 is a piece of canvas having a slit 18 therein for the purpose of inserting the pneumatic bladder 19 within the upper structure. Top closure 17 is secured around the edge of the dummy at 20.

The lower edge of the upper portion is stitched 20 to the pneumatic ring covering at 21. The base portion has two layers of canvas 23 and 24 which are sewed together substantially as is the upper portion, and has a closure consisting of two layers 25 and 26 which are stitched to the parts 23 and 24 at 27. The casing for the pneumatic ring is stitched to the upper and lower sections at 21 and 22 respectively. The pneumatic ring covering 28 has a piece of material 29 which is stitched at 30 and 31 forming substantially a circular fabric casing for the inflatable rubber ring 32 which ring is in appearance substantially an inner tube such as is used in an automobile tire. The inflatable ring has a valve 33 which communicates with the exterior of the tubular ring casing for the purpose of inflating the ring. The upper bladder 19 has a valve or port 34 which communicates with the exterior of the upper casing for the purpose of inflating the bladder 19.

The lower section requires a ballast which in 40 the present case is sand and is enclosed in a container or bag 36 which bag has two flaps 37 and 38 stitched at 39 and 40. The ends of the flaps are folded together at 41 and are either sewed or laced. Commercially both methods are used. 45 However, any confining method such as a mechanical fastener may be employed since the object is merely to effect a suitable closure to prevent the sand or other ballast from escaping from its container.

The bladder 19 is inserted through the opening 18 in the top, the bottom part of the bladder resting on the top part of the ballast container. The inflatable ring casing has flaps 42 and 43 which overlap and are laced by such as a raw hide strap 44. The top part of the upper casing 17 has

leather members 45 sewed thereon which form an integral part of the opening 18. The upper opening is closed by lacing 46. The opening 47 for the valve, in the casing, is shown clearly in Fig. 1.

Fig. 2 shows the flaps 37 and 38 of the ballast bag 36. A part broken away in Fig. 2 shows the inflatable ring 32 and the outer canvas strip 29 engaging said tube or ring.

Fig. 4 shows specifically in detail two layers of leather 43 and 48 having two layers of canvas 49 and 50 where it is desirable to use two layers of material for the top covering of the bag. The flaps 51 and 52 go over the top of the bladder 18 so that the lacing 46 does not engage the bladder 18 per se. The valve 34 is actually the valve stem with the valve enclosed.

Fig. 5 shows the valve 33 secured to the tube or ring 32 which has the fabric side 28 stitched at 29 to a leather supporting material 53. 50 in Figs. 4 and 5 is a nut which is threadedly connected to the valve stem per se.

Handles 66 are stitched to the upper casing and are used for carrying the dummy when not in use.

The ballast is of sufficient weight and is located in a container of sufficient width to retain the center of gravity within the confines of the pneumatic ring or tube so that when the dummy is knocked over it will always be brought back in an erect position by gravity.

From the foregoing it will be seen that the dummy is of the self erecting type having a container which utilizes a filler such as sand to give the dummy self erecting qualities, and also afford sufficient resistance to the impact of a football player when the dummy is contacted by the player. The dummy has an inflatable bladder in the upper portion thereon which can be removed for repair or renewal. The pneumatic tube or ring is held in position by lacing together opposing flaps which form a closure for the tube.

It will be seen that the present dummy can have the sand removed from the ballast bag, and both the pneumatic ring or tube, and the bladder can be deflated so that when the dummy is packed for shipping the size and weight of the dummy is materially reduced as compared with the dummy when ready for use.

While specific details of this invention have been herein shown and described, the invention is not confined thereto as changes and alterations may be, and may become apparent to those skilled in the art without departing from the spirit thereof as defined by the appended claims.

Having thus described the invention, what I claim as new and desire to secure by Letters Patent of the United States is:

1. A collapsible football dummy of the class described comprising an outer casing, a ballast container having an opening therein to permit the ballast to be inserted located in the lower portion of the said casing, a resilient circular means at the lower portion of the casing, and an inflatable member located above the ballast container.

2. A self-erecting football dummy having an outer casing, means to receive ballast located in the lower portion of the casing, an inflatable member within said casing located above last said

means, an inflatable circular member within said casing, and securing means about the inflatable member to hold same in fixed relation to the casing.

3. A football dummy of the class described comprising an outer casing, a ballast receiving container having a closure means therefore, a circular inflatable member in the lower portion of the casing and closure means therefore, an inflatable member in the upper portion of the casing and a closure in the top of said casing.

4. A football dummy of the self-erecting type having a resilient upper portion to receive the impact of a player, a weight retaining means secured to the bottom of the upper portion, said weight retaining means having substantially a flat bottom to retain the dummy in a normally upright position, and a closed ring of resilient material secured about the lower half of the dummy, said ring of resilient material being stitched to the dummy by spaced rows of stitching to hold the ring in substantially fixed relation to the dummy.

5. A football dummy of the self-erecting type comprising an upper portion, resilient means within said upper portion to hold same in a distended condition, a lower portion comprising a flexible ballast receiving container secured at the base of the upper portion of the dummy, and a distended shell of flexible material secured to the upper and lower portions of the dummy.

6. A football dummy of the self-erecting type comprising an upper portion, resilient means within said upper portion to hold same in a distended condition, a pliable ballast receiving container secured at the base of the upper portion of the dummy, a shell of flexible material forming a complete circle about the dummy and stitched thereto substantially adjacent where the upper portion is connected to the resilient ballast receiving container, and means within said shell to hold same distended, whereby when the dummy is sufficiently moved from its normally upright position the distended shell will engage the ground to prevent the dummy from assuming a horizontal attitude.

7. A football dummy of the self-erecting type having a unitary casing of pliable material, granular ballast means located in the lower portion of the dummy, an inflatable member within said casing located above the ballast means, a closed circular shell of pliable material connected to said unitary casing, and resilient means within said shell to hold same distended when ready for use.

8. A self-erecting football dummy of the class described comprising a resilient upper portion, a ballast retaining means below the upper portion and securely connected thereto, a protruding member being substantially round in a vertical cross-section thereof secured substantially at the lower portion of the dummy and extending around said dummy, whereby the protruding member acts as a limiting means which tends to restrict the angular displacement of the dummy to less than a 90° angle from a normally upright position in the normal operation of the dummy.

MARTIN JOHN GILMAN.
